DESIGN FOR A COMBINED CHRISTMAS
WREATH, ORNAMENT, AND CANDLE

Leo Pollock, New York, N. Y.

Application March 30, 1935, Serial No. 56,134

Term of patent 7 years

To all whom it may concern:

Be it known that Leo Pollock, a citizen of the United States and resident of New York city, in the county of New York and State of New York, has invented a new, original, and ornamental Design for a Combined Christmas Wreath, Ornament, and Candle, of which the following is a specification, reference being had to the accompanying drawing, forming part thereof, in which,

Fig. 1 is a front elevational view of a combined Christmas wreath, ornament and candle embodying my new design; and

Fig. 2 is a side elevational view thereof.

The Christmas wreath embodying the design comprises a wreath A in front of which is mounted a bell-shaped ornament B having a translucent sheet C through which the electric bulb D shines when illuminated.

I claim:

The ornamental design for a combined Christmas wreath, ornament, and candle, substantially as shown and described.

Dated, New York city, March 27, 1935.

LEO POLLOCK.
